[57] **CLAIM**

The ornamental design for a portion of a shoe upper, as shown and described.

DESCRIPTION

FIG. 1 is a side elevational view of a portion of a shoe upper showing my new design;

FIG. 2 is a rear elevational view of the portion of a shoe upper of FIG. 1;

FIG. 3 is a front elevational view of the portion of a shoe upper of FIG. 1; and,

FIG. 4 is a top plan view of the portion of a shoe upper of FIG. 1.

The broken line showing of a shoe sole and the remainder of the shoe upper is for illustrative purposes and forms no part of the claimed design.
